CIRCUIT BREAKER WITH MECHANICALLY ISOLATED TRIP MECHANISM

Leonide P. Koval, Far Rockaway, N.Y., and Maurice E. Sirois, Plainville, Conn., assignors to General Electric Company, a corporation of New York

Filed May 3, 1962, Ser. No. 192,192

9 Claims. (Cl. 200—88)

The present invention relates to electric circuit breakers, and particularly to electric circuit breakers of the type comprising a main molded insulating enclosure or case containing relatively fixed and movable contacts and manually operable operating mechanism therefor, including a releasable member for causing automatic opening of the contacts, and a separately enclosed current-responsive mechanism or trip unit contained within the main enclosure or case and adapted to cause release of the releasable member and automatic opening of the contacts upon the occurrence of predetermined current conditions through the circuit breaker.

Such separately enclosed current-responsive mechanisms or trip units are commonly adjusted or calibrated to cause automatic opening of the circuit breaker upon the occurrence of particular predetermined current conditions, before the trip unit is mounted in the main case of the circuit breaker. This not only facilitates the necessary adjustments to the trip unit, but permits the changing of trip units by the user.

Commercially usable circuit breakers and trip units heretofore available have suffered from the disadvantage that when a pre-adjusted or "calibrated" trip unit is mounted in a circuit breaker, it is sometimes found that the trip unit does not operate within the preset range of current conditions. This has been discovered to be due to two main factors: (1) the fact that the contact operating mechanisms of such circuit breakers may vary slightly from one to the other in the degree of force tending to operate the releasable means thereof, and (2) the fact that unavoidable variations in the dimensions and characteristics of the main insulating casing and of the contact operating mechanisms thereof from one breaker to another are such that the force and amount of movement required to release the releasable means of the contact-operating mechanism is altered thereby.

It is an object of the present invention to provide an electric circuit breaker of the type referred to comprising a pre-calibratable trip unit whose adjustment or point of operation is not altered by minor variations in mounting of the trip unit in the main casing or by minor variations in the force tending to operate the releasable means of the contact operating mechanism.

It is another object of the invention to provide a trip unit of the type described the setting or calibration of which is unaffected by variations in mounting or operating mechanism force and which requires no corresponding special modification of the circuit breaker operating mechanism.

It is a further object of the invention to provide a pre-calibratable trip unit of the type described which requires the use of a minimum number of parts.

In accordance with the invention, a circuit breaker is provided comprising a main casing including relatively fixed and movable contacts and manually operable operating mechanism therefor including a first member releasable to cause automatic opening of the contacts, and a separately enclosed trip unit mounted in the main casing and including a first restraining means for releasably restraining the first releasable member. Means is also provided in the trip unit for moving said first restraining means, comprising a second releasable member, biased

2

to cause movement of the first restraining means, and releasably held against such movement. The trip unit of the present invention further includes means for causing release of the second releasable member in response to predetermined current conditions.

Further, in accordance with the invention, the force exerted by the second releasable means within the trip unit is made appreciably greater than the force normally required to move the said first restraining means. The excess of the force exerted by the second releasable means over that normally required to move the first restraining means is such that ordinarily encountered variations in the force required to move the said first restraining means have no effect on the operation of the trip unit.

The invention will be more fully understood from the following detailed description, and its scope will be pointed out in the appended claims.

In the drawings,

FIGURE 1 is a side elevation view of an electric circuit breaker incorporating the invention, a portion of the side wall of the main casing being broken away;

FIGURE 2 is an end elevation view of the trip unit of the circuit breaker of FIGURE 1, taken on the line 2—2 of FIGURE 1;

FIGURE 3 is a sectional view of the trip unit of the circuit breaker of FIGURE 1, taken substantially on the line 3—3 of FIGURE 2;

FIGURE 4 is a view of a portion of the mechanism of the trip unit as shown in FIGURE 3, shown in releasing position; and

FIGURE 5 is a perspective view of the latching mechanism of the trip unit of FIGURES 1—4.

Referring first to FIGURE 1, the invention is shown as incorporated in a circuit breaker comprising a main molded insulating enclosure or case 10, containing three incoming and three outgoing terminal means 11 and 12 respectively, only one of each shown.

A pair of relatively movable contacts 13, 14 is provided connected between each terminal 11 and a corresponding terminal 12. The contact 13 is rigidly mounted on the terminal conductor 11, while the contact 14 is mounted on a contact support 15 pivotally supported at 16 on a movable contact arm 17, and a compression spring 15A is provided therebetween. The contact arm 17, in turn, is rigidly supported on a contact cross-arm 18, pivotally supported at its ends on suitable bearings, not shown, mounted in the base of the casing 10.

It will be understood that the cross-arm 18 extends across all three poles of the circuit breaker, and carries three contact arms 17, although only one, the central of the three, is shown in FIGURE 1.

Each contact support 15 is connected by a flexible conductor or braid 19 to a corresponding terminal strap 20 of the trip unit 21, to be described more fully. Each terminal strap 20 of the trip unit 21 is electrically connected to a corresponding outgoing terminal strap 12.

Contact operating mechanism.—For the purpose of operating the contacts 13, 14 between open and closed condition, an operating mechanism is provided, comprising a manually engageable handle member 22, mounted on a generally U-shaped handle support member 23 pivotally supported on a fixed pivot pin 24 carried by a stationary supporting frame, not shown, mounted in the casing 10.

A releasable member 25 is also pivotally supported on a fixed pivot pin 26 carried by the supporting frame.

A pair of toggle-links 27, 28 are connected between the releasable member 25 and the contact arm 17, at pivots 29 and 30 respectively, and are interconnected by a knee pivot pin 31.

A tension spring 32 is connected between the handle-

support member 23 and the knee pivot pin 31 of the toggle linkage.

In operation, the handle 22 is oscillated about its pivot 24 from the "ON" position shown in FIGURE 1 to the left as viewed to an "OFF" position, moving the tension spring 32 across the line of centers of the pins 31 and 29, moving the toggle linkage 27, 28, to a collapsed condition, and moving the contact arm 17 upwardly to an "OFF" position.

The releasable member 25 has a latch portion 25A, see FIGURES 3 and 4, which is releasably held by a latch carried by the trip unit 21 in a manner to be described.

When the operating mechanism is in the "ON" condition as shown in FIGURE 1, release of the releasable member 25 permits this part to move clockwise about its pivot 26 under the influence of the tension spring 32, moving the contact arm 17 upwardly to "OFF" position and causing collapse or partial collapse of the toggle linkage 27, 28.

Subsequent resetting of the member 25 is accomplished by manually moving the handle 22 to "OFF" position, causing an extension 23A of the handle support member to engage the member 25 and rotate it counterclockwise to a relatched position.

Trip unit

Referring now particularly to FIGURES 2-5, the trip unit 21 comprises a separate insulating casing including a box-like body 35 having one open side wall, closed by a cover member 36 attached thereto by suitable means, not shown.

Each outgoing terminal strap 12 is rigidly affixed to the case 35 by means of screws 37. Each incoming terminal strap 20 is fixedly attached to the case 35 by means of screws 38.

The trip unit as a whole is fixedly mounted in the case 10 by means of screws 39 which serve to attach the flexible conductors 19 to the straps 20 and also pass through the straps 20 and threadedly engage tapped inserts 40 in the base of the case 10.

The strap 12 is connected to the strap 20 by a conductor 42, which makes a complete turn about a first magnetic core 43, extending between two generally planar magnetic side plates 44, only one shown.

A second magnetic core 45 is also supported between the side plates 44. Mounted on the core 45 in insulated relation, is a loop or ring 46 of highly conductive material such as copper.

A thermally-responsive member, comprising an elongated bimetallic strip 47, is rigidly affixed to the loop 46 by suitable means, such as by welding.

In operation, current passing from the strap 12 to the strap 20, through the conductor 42 causes that conductor to act as the primary of a transformer, setting up magnetic flux through the magnetic path comprising the core 43, side plates 44, and core 45. This causes a secondary current to be induced in loop 46, generating heat therein. The heat generated in loop 46 is transferred by conduction to the bimetallic strip 47, which is so constructed and arranged as to deflect to the right as viewed, moving the adjusting screw 48 to the right to cause tripping or release of the releasable means in a manner to be described.

It will be understood that as previously mentioned, three outgoing terminal straps 12 and incoming straps 20 are provided, each having associated therewith, parts as illustrated in FIGURE 3 including conductors 42, magnetic systems including cores 43, side plates 44, and cores 45, as well as conductive loops 46 and bimetallic strips 47 with adjusting screws 48.

Latching mechanism

In accordance with the invention, latching means is provided including a common trip bar 50 of molded insulating material, extending across all three poles of the

circuit breaker trip unit, and adapted to be rotated about its pivot 51, by the bimetallic strips 47.

The common trip bar 50 is also adapted to be rotated about its pivot 51 by magnetic action. For this purpose, 5 the side plates 44 are provided with pole extensions 44A. A magnetic armature 52 is also provided at each pole, pivotally supported, independently of the trip bar 50, on the pivot pin 51. Each armature 52 has an extension 52A having a portion adapted to engage a portion of the trip bar 50 to rotate it clockwise when the armature 52 is attracted to the pole extensions 44A.

The molded insulating trip bar 50 includes a centrally-located extension 50A, having a rounded end portion 50A' disposed to engage an arm 53, see FIGURE 5 of the latching mechanism which will now be described.

Referring particularly to FIGURES 3-5, the latching mechanism of the invention comprises a supporting frame 54, see FIGURE 5, comprising two opposed side portions 55, 56, joined by a bight portion 57, and supported within an aperture 36A, see FIGURE 2, in the cover 36. The side portions 55, 56 each include an outwardly-directed tang 71, 71' respectively, having holes 72, 72', by which the frame 54 is adapted to be rigidly attached to the cover 36 of the trip unit housing by suitable means such as by screws, not shown.

For the purpose of releasably restraining the primary releasable member 25, the latching mechanism includes a primary latch member 58 pivotally supported between the sides 55, 56 on pivotal supports 59. The primary latch member 58 includes a latching portion 58A adapted to engage the latch portion 25A of the releasable member 25.

For the purpose of causing releasing movement of the primary latch member 58 upon the occurrence of predetermined current conditions, a tripping or "kick-off" member 60 is provided, pivotally supported on a pivot pin 61, extending between the sides plates 55, 56.

The tripping or "kick-off" member 60 includes an extension 60A having a notch 60B, providing a secondary latch surface.

In the normal condition of the parts, as shown in FIGURE 3, the "kick-off" member 60 is releasably restrained from counter-clockwise movement by engagement of an arm 62 of a secondary latch member 63.

The secondary latch member 63 is pivotally supported on pivot pin 64 extending between the sides 55, 56 of the frame 54. The secondary latch member 63 is generally U-shaped, having a bight portion extending generally parallel to the pin 64, a latch arm 62, and an actuating arm 53.

The secondary latch 63 is biased clockwise about its pivot pin 64 by the action of one end portion 65 of a coil spring 66, acting on a pin 67 carried by the arm 53. The other end, 68, of the spring 66 engages the primary latch member 58, and biases it in a clockwise direction.

The primary latch member 58 includes a downwardly directed extension 58B, see FIGURE 3, which engages the pin 61 to limit movement of the member 58 in counter-clockwise direction as viewed in FIGURE 3.

The secondary latch member 63, at its arm 62, engages a wall of the notch 60B of the arm 60A of the "kick-off" member 60 as a stop to limit movement of the member 60 in counterclockwise direction. It will be observed that this provides a fixed accurately controllable amount of latch overlap of the secondary latch arm 62 and the tripping member 60.

For the purpose of biasing the "kick-off" member 60 in counter-clockwise direction as viewed in FIGURE 3, a "kick-off" spring 70 is provided, carried by the pin 61. One end 70A of the spring 70 is normally in engagement with the casing cover 36, while the other end 70B, is in engagement with an edge portion of the member 60.

For the purpose of engaging and moving the primary latch member 58, the "kick-off" member 60, at its right

side as viewed in FIGURE 5, includes two actuating projections. The first such projection is designated as 60C, see FIGURE 4, and the second such projection is designated as 60D, also in FIGURE 4.

It will be observed by reference to FIGURE 3, that projection 60C is normally substantially in engagement with the extension 58B of the primary latch 58. The projection 60D, of the "kick-off" member 60 is normally spaced a short distance from a corresponding surface 58C of the member 58.

It will be observed that the latching system just described comprises a primary latch member 58, restraining the releasable member 25, and a secondary latch member 63, restraining the "kick-off" member 60. All of the aforesaid members are preferably mounted on the 15 cover member 36 of the trip unit 21. This permits these parts to be readily assembled before the cover member is mounted on the enclosure body 35.

It will be observed, moreover, that in the normal condition of the parts as indicated in FIGURE 3, these latch 20 systems are independent of each other. In other words, the primary latch is biased against the pin 61 as a stop, and is unaffected by movement of the secondary latch 63 until the "kick-off" member 60 is released.

In operation, therefore, the occurrence of predetermined abnormal current conditions in the circuit including terminal straps 12 and 20 and conductor 42 causes rotation of the common trip bar 50. This may occur by reason of the heating and deflection of the bimetallic strip 47 as on gradual overload currents, or by reason of the 30 attraction of the armature 52 to the pole extensions 44A as on the sudden high short-circuit currents.

Rotation of the trip bar 50 causes engagement of the projection 50A of the trip bar 50 with the arm 53 of secondary latch 63. Rotation of the secondary latch 63 a 35 predetermined amount causes release of the "kick-off" member 60.

Upon release, the member 60 is moved by spring 70 in a counter-clockwise direction.

During the initial portion of its movement, the projection 40 60A of the member 60 engages the extension 58B of the member 58, providing a pry-off action to overcome static friction of the latch 58A of the member 58 and the latched portion 25A of the member 25.

Subsequent movement of the member 60 causes the 45 projection 60D to engage the edge surface 58C of the member 58 to move it to fully released position, releasing the member 25 to cause opening of the contacts of the breaker.

Following release of the releasable member 25, the 50 parts may be reset to permit subsequent reclosing of the contacts. Such resetting is accomplished by moving the handle 22 counterclockwise, causing projection 23A of the handle-support member 23 to engage the releasable member 25 and rotate it also in counter-clockwise direction.

Referring to FIGURE 4, when the member 25 is thus rotated counter-clockwise, it moves downwardly toward the tripping member 60, and engages the edge portion 60E of the member, rotating it clockwise to permit the 60 arm 62 of the secondary latch member to drop into the notch 60B. The primary latch 58 is simultaneously moved to latching position against the pin 61 and engages the tip 25A of the member 25 when it moves upwardly.

For the purpose of ensuring release of the primary latch member 58 upon release of the "kick-off" member 60, the "kick-off" spring 70 is made of such strength as to be capable of delivering a force substantially greater than that required to release the primary latch 58.

By this means, it is possible to calibrate or adjust the trip unit 21 apart from the main circuit breaker, with the assurance that the setting will not be disturbed although the force required to move the primary latch 58 may vary within certain pre-determinable extremes because of variations of the mounting of the trip unit 21 in the case 10, 70 75

or because of variations in the force necessary to restrain the releasable member 25.

It will be observed, also, that the critical isolation of the calibration of the trip unit 21 is accomplished in accordance with the invention, by the use of a single secondary latch member, which is acted upon by the common trip bar, which in turn is acted upon by the current responsive means (either the bimetallic strips 47 or the magnetic armatures 52) of each pole of the circuit breaker.

While only one embodiment of the invention has been described, it will be appreciated that many modifications thereof may be made, and it is intended, therefore, that the appended claims shall cover all such modifications as fall within the true spirit and scope of the invention.

We claim:

1. A multi-pole electric circuit breaker comprising:
  - (a) a main insulating casing,
  - (b) at least two pairs of relatively movable contacts supported in said casing,
  - (c) manually operable operating mechanism in said main casing for moving said contacts between open and closed circuit positions and including a member releasable to cause automatic opening of said contacts,
  - (d) a primary latch disposed and arranged to releasably engage said releasable member of said operating mechanism,
  - (e) a separately enclosed trip unit removably mounted in said main insulating casing,
  - (f) a tripping member carried by said trip unit, biasing means carried by said trip unit separate from said operating mechanism acting on said tripping member and biasing said tripping member to exert a force on said primary latch,
  - (g) a secondary latch carried by said trip unit releasably restraining said tripping member,
  - (h) a common trip bar carried by said trip unit and extending across all poles of said multi-pole circuit breaker,
  - (i) at least one current-responsive means carried by said trip unit for each of said poles and disposed and arranged to engage said common trip bar and,
  - (j) said common trip bar including means for causing release of said secondary latch upon a predetermined amount of movement of said common trip bar by said current-responsive means,
  - (k) said tripping member when released acting on said primary latch to cause release of said releasable member.
2. A multi-pole electric circuit breaker comprising:
  - (a) a main insulating casing,
  - (b) at least two pairs of relatively movable contacts supported in said casing,
  - (c) manually operable operating mechanism in said main casing for moving said contacts between open and closed circuit positions and including a member releasable to cause automatic opening of said contacts,
  - (d) a separately enclosed trip unit removably mounted in said main insulating casing,
  - (e) a primary latch carried by said trip unit and disposed and arranged to releasably engage said releasable member of said operating mechanism when said trip unit is mounted in said main casing,
  - (f) a tripping member carried by said trip unit, biasing means carried by said trip unit separate from said operating mechanism acting on said tripping member and biasing said tripping member to exert a force on said primary latch,
  - (g) a secondary latch carried by said trip unit releasably restraining said tripping member,
  - (h) a common trip bar carried by said trip unit and extending across all poles of said multi-pole circuit breaker,

- (i) at least one current-responsive means carried by said trip unit for each of said poles and disposed and arranged to engage said common trip bar and,
  - (j) said common trip bar including means for causing release of said secondary latch upon a predetermined amount of movement of said common trip bar by said current-responsive means
  - (k) said tripping member when released acting on said primary latch to cause release of said releasable member.
3. A multi-pole circuit breaker as set forth in claim 2, said trip unit including a generally box-like insulating enclosure having an open side wall and a generally planar insulating cover member attached to said enclosure and closing said open side wall, said primary latch, said tripping member and said secondary latch being carried by said cover member.
4. A multi-pole circuit breaker as set forth in claim 1 wherein said tripping member includes an integral stop portion which determines the amount of latch engagement of said secondary latch member with said tripping member.
5. A multi-pole circuit breaker as set forth in claim 1 wherein said current responsive means comprises an elongated bimetallic strip for each pole of said circuit breaker having means thereon for engaging said common trip bar, and wherein said current responsive means also comprises a magnetic armature for each pole of said circuit breaker, said armatures each being movable to cause releasing movement of said secondary latch independently of said bimetallic strips.
6. A multi-pole circuit breaker as set forth in claim 2, said tripping member having a first portion thereof adapted to engage said primary latch member at a first point and a second portion thereof adapted to engage said primary latch at a second point, said first point of engagement being spaced farther from the pivot of said primary latch than said second point.
7. A multi-pole electric circuit breaker comprising:
- (a) a main insulating casing,
  - (b) at least two pairs of relatively movable contacts supported in said casing,
  - (c) manually operable operating mechanism in said main casing for moving said contacts between open and closed circuit positions and including a member releasable to cause automatic opening of said contacts,
  - (d) a trip unit removably mounted in said main insulating casing and including a trip unit insulating casing,
  - (e) a primary latch disposed and arranged to releasably engage said releasable member of said operating mechanism when said trip unit is mounted in said main casing,
  - (f) said trip unit having a tripping member, biasing means carried by said trip unit separate from said operating mechanism acting on said tripping member and biasing said tripping member to exert a force on said primary latch, said tripping member when released acting on said primary latch to cause release of said releasable member,
  - (g) said trip unit having a secondary latch normally releasably restraining said tripping member,
  - (h) said trip unit having a common trip bar extending across all poles of said multi-pole circuit breaker,
  - (i) at least one current responsive means carried by said trip unit for each of said poles and each dis-

posed and arranged to engage said common trip bar,

(j) said common trip bar including means for causing release of said secondary latch upon predetermined movement of said common trip bar by said current responsive means,

(k) said trip unit being mounted in said main casing with a predetermined wall portion of said trip unit casing adjacent said operating mechanism,

(l) a metallic frame member mounted on said predetermined wall of said trip unit casing, said frame member having a pair of spaced apart side portions,

(m) said primary latch member and said tripping member both being carried by said metallic frame member between said opposed side portions,

(n) said predetermined wall of said trip unit casing having an opening therein,

(o) said frame member being supported on said wall adjacent said opening to permit said primary latch member to cause release of said releasable member of said operating mechanism and said common trip bar to cause releasing movement of said tripping member.

8. A multi-pole electric circuit breaker as set forth in claim 7 wherein said primary latch member cooperates with said releasable member outside of said trip unit casing and said tripping member cooperates with said secondary latch means inside said trip unit casing.

9. A multi-pole electric circuit breaker as set forth in claim 7 wherein

(a) said main casing includes a bottom wall supporting at least one of each of said pairs of relatively movable contacts and said manually operable operating mechanism, said trip unit casing being mounted on said bottom wall, with said predetermined wall portion of said trip unit casing extending substantially perpendicular to said bottom wall,

(b) said side portions of said bimetallic frame member also extending substantially perpendicular to said back wall,

(c) said primary latch member being pivotally supported between said side portions of said frame member,

(d) said tripping member being pivotally supported between said side portions of said frame member at a point substantially closer to said back wall than said primary latch member.
